METHOD FOR KNITTING HOSIERY

Rheubin L. Bunton, Hickory, N. C., assignor to
George W. Grove, Hickory, N. C.

Application June 21, 1937, Serial No. 149,539.

3 Claims. (Cl. 66—41)

This invention relates generally to anti-ravel mock ribbed-top seamless hosiery; and, more particularly to mock ribbed-top seamless stockings and a method and machine for producing the same.

One object of the invention is to provide a method of knitting on a circular knitting machine a mock ribbed-top stocking from top to toe, starting from the bare needles.

Another object of the invention is to modify 10 and improve a circular knitting machine to enable it to knit a mock ribbed-top stocking from top to toe, starting at the top with the bare needles.

A further object of the invention is to provide 15 a mock-ribbed-top stocking, having the top course laid in as an anti-ravel course, with the next course knitted thereto and to the succeeding courses.

Still another object of the invention is to provide 20 a mock ribbed-top stocking having the first and second courses of the top formed of elastic yarn with the first course laid in as an anti-ravel course and succeeding courses knitted.

Other objects of the invention will become apparent as the detailed description thereof proceeds.

In the drawings:

Figure 1 is a fragmentary perspective of a 30 knitting machine involved in the present invention;

Figure 2 is a fragmentary elevation of the upper part of a mock ribbed-top stocking constructed in accordance with the present invention;

Figure 3 is a development of part of the knitting wave and cams of a Scott and Williams revolving needle cylinder machine, modified to carry out the method involved in the production of the stocking shown in Figure 2;

Figure 4 is a fragmentary elevation of mechanism for clamping and cutting an elastic yarn used to form the first two courses of a mock ribbed-top stocking; and

Figure 5 is a diagram illustrating the formation of the upper part of the stocking.

The stocking resulting from my method of knitting as a single ply weld; that is, the top thereof is of a single thickness. It is knitted from top to toe and can be started on bare needles. The stocking 6 comprises a mock ribbed-top 7 connected by transfer 8 to the leg 9. The first two courses 10 and 11 are formed of covered rubber yarn; the first course being laid in with the second course knitted thereto. Upon

the completion of the second course the elastic yarn is clamped and severed, and the knitting continued with the plain yarn.

In carrying out this invention, the knitting 5 machine is modified by providing the needle bank with two sets of jacks; one set raising every fourth needle to a predetermined height about the top of the normal needle bank, and the other set raising every second needle to a height intermediate the height of the fourth needles and those of normal height. Thus in the operation of the machine, there are three sets of needles of different heights. The needles, in the upper row 12 are raised by jacks 12' of a predetermined length, while those in the intermediate row 13 are raised by shorter jacks 13'. No jacks are used with the remaining lowermost row of needles 14.

The mock ribbed-top 7 of the sock or stocking 6 is knitted by the two upper rows. While this top is being knitted the lower row is depressed by a special sliding cam 15, so as to pass under the stitch cams 16 and 17 without being affected thereby. The transfer from the top 7 to the leg 9 is effected by sliding the cam 15 out of the path of the lower ends of the needles, thereby leaving all the needles in position for operation by the stitch and draw down cams in the usual manner.

In starting the operation, the elastic yarn 18 is moved by an adjustable yarn feed 19 into the position, shown in Figure 3, where the yarn will be laid in the hooks of the uppermost row of needles 12. The thread is thus caught by every fourth needle of the complete needle bank. Since the needle bank is cylindrical, the thread between adjacent needles of the top row forms chords to the complete cylinder of needles; and as the intermediate needles are raised under the 35 action of the stitch cams, the chords pass behind the intermediate row of needles 13.

Upon completion of the first elastic course 10, the elastic yarn feed 19 drops to the level of the intermediate row 13, so that all the needles in both rows 12 and 13 may catch the thread; and the second elastic course 11 is knit, using every other needle of the entire needle bank. The elastic yarn is then held and severed by the clamping mechanism designated generally by the 45 reference numeral 20; and the inelastic yarn 21 fed to the machine.

The knitting of the mock ribbed-top is continued, by operation of the two upper rows of needles, through the desired number of courses. Then the transfer is effected automatically by

removal of the slide 15 from the path of the lowest row. All the needles of the entire needle bank then operate to complete the leg 9 of the stocking.

The invention is not concerned with the structural details of the yarn feed or clamping and severing mechanism, since these are old and well known in this art. The novelty mainly resides in the use of two sets of jacks of different heights to raise every second and fourth needle of the entire needle bank to different heights above the remaining needles, while the latter are removed by the slide cam from operative contact with the stitching cams. This construction renders it possible to knit mechanically a complete mock ribbed-top stocking, starting with the bare needles and knitting through the transfer from top to toe.

What I claim is:

1. The method of knitting an anti-ravel mock ribbed-top stocking on a circular knitting machine which consists in laying the yarn of the first course in the hooks of every fourth needle, feeding the yarn of succeeding courses to the hooks of the second and fourth needles until the

mock ribbed-top is completed and then knitting in succession on all needles to complete the stocking.

2. The method of knitting an elastic welt mock ribbed-top stocking on a circular knitting machine which consists in laying an elastic yarn as a first course in the hooks of every fourth needle, feeding the same elastic yarn as a second course to the hooks of all of the second and fourth needles, substituting an inelastic yarn for the elastic yarn and feeding said inelastic yarn to the hooks of the second and fourth needles until the mock ribbed-top is completed, and then knitting in succession on all needles of the needle bank to complete the stocking.

3. The method of knitting an elastic welt mock ribbed-top stocking on a circular knitting machine, which consists in feeding an elastic yarn as a first course to the hooks of every fourth needle, substituting an inelastic yarn for the elastic yarn, feeding the substituted yarn to the hooks of the second and fourth needles until the mock ribbed-top is completed, and then knitting on all needles to complete the stocking.

RHEUBIN L. BUNTON.
